DRILL UNIT

Darwin B. Grossman, New Rochelle, N. Y.

Application May 3, 1950, Serial No. 159,669

3 Claims. (Cl. 77—33.5)

1

This invention is a pneumatically operable drill unit designed for high speed drilling with its air cylinder forming an integral part of the unit.

One object of the invention is to provide a unit of small dimensions and compact construction to permit a plurality of these units, when mounted in gang, to position the drill tools relatively close to one another for multiple drilling.

A further object of the invention is to provide a drill unit of great simplicity and one which may be economically manufactured and sold at a relatively low price.

In the unit of this invention, the drill bit is supported in a chuck mounted upon a rotatable spindle embraced by a tubular piston stem on which the pneumatic piston is rigidly supported, the spindle and piston stem being axially movable as a unit and the spindle rotatable with respect to the stem. The stem is supported at its opposite ends in bearing blocks which extend to one side of the unit and are there rigidly tied to one another by a stop rod arranged parallel to the stem and adapted to reciprocate therewith. This rod passes through a bearing in the body of the unit in which the cylinder is formed and said bearing is of such length as to maintain the stem and rod at all times in parallel relation. This support of the piston stem eliminates bending stresses on the stem and spindle and assures more accurate boring, as will hereinafter be more fully explained. The stop rod serves the additional purpose of limiting the throw of the piston in both directions to a predetermined zone of operation and thus controls the depth of the drilled holes.

Features of the invention, other than those adverted to, will be apparent from the herein-after detailed description and appended claims, when read in conjunction with the accompanying drawing.

The accompanying drawing illustrates one practical embodiment of the invention, but the construction therein shown is to be understood as illustrative, only, and not as defining the limits of the invention.

Figure 1 is a vertical diametric section through the unit taken on the line 1—1 of Figure 2.

Figure 2 is a like view taken on the line 2—2 of Figure 1.

Figure 3 is a section on the line 3—3 of Figure 1.

Figure 4 is an elevation showing the piston stem, its bearing blocks, stop rod and the spindle removed from the remaining parts of the unit.

Referring to the drawings, 1 designates the

2

body of the unit. It is of elongated form and of the cross section shown in Figure 3. Its structure is such that it may be either cast or extruded for economy in production. In one side of the body is formed a cylinder 2, the opposite ends of which are internally threaded, as at 3. Extending parallel of the cylinder, but at the opposite side of the body is a circular hole 4 which extends through the entire height of the body. 10 This hole serves as a guide bearing for a stop rod 5 hereinafter described.

The upper and lower ends of the cylinder are closed by end caps 6 and 7, these caps having reduced threaded portions adapted to screw into 15 the threads 3 of the cylinder to rigidly mount the caps at the opposite ends of said cylinder. Each of these end caps 6 and 7 is bored and counter-bored to provide an inwardly facing shoulder 8 and within each cap is positioned a 20 sleeve 9. The inner end of each sleeve has an external flange 10 adapted to be tightly seated against the corresponding shoulder 8 of the end caps by a sleeve nut 11, threaded on to the exterior of the sleeve and bearing against the outer 25 face of the cap to rigidly support the sleeve 9 upon the cap.

Operable within the cylinder 2 is a piston 12. This piston is affixed to a tubular piston stem 13 which extends upwardly through the upper sleeve 9 and downwardly through the corresponding lower sleeve with close sliding fit. Suitable packings 14 with packing nuts 15 preclude leakage between the piston stem and the sleeves 9.

35 The piston may be either single or double acting but, for the purpose of illustration, I have shown it double acting. When so made, it may conveniently comprise a pair of opposed cup washers 16 positioned back to back against an 40 interposed disk and held in place by spring retainers 17, seated in circular grooves in the piston stem above and below external disks 18. The upper and lower ends of the piston stem 13 are reduced beyond shoulders 19 and said reduced 45 ends extend into openings in upper and lower bearing blocks 20 and 21, respectively. In each of such openings, beyond the ends of the piston stem, are positioned anti-friction bearings 22, shown as ball bearings. The outer races of these 50 bearings are supported in the blocks 20 and 21, while the inner races embrace the spindle 23. Spring retainers 24 seat in grooves in the spindle externally of the anti-friction bearings and serve to retain the bearing blocks on the piston stem 55 and lock the stem and spindle against relative

axial movement, while permitting free rotation of the spindle relative to the piston stem.

The spindle is provided at its lower end with a chuck to hold a drill bit or other tool and on the upper end of the spindle is secured a pulley 25 by which the spindle is belt rotated from any suitable prime mover. The pulley is shown with its hub supported for rotation in an anti-friction bearing 26 mounted in the upper portion of a cage-like extension 27, the lower end of which embraces the upper sleeve nut 15 and is secured thereto by a force fit, set screws, or in any other suitable manner.

When thus mounted, the pulley must be slidably mounted on the spindle. This sliding connection may be in the form of an ordinary bar key and slot connection. However, I prefer to form a slot in the shaft, a registering slot in the pulley hub, and utilize as the key, one or more steel balls 27 (similar to ball bearings) held in place in the hub of the pulley by a retaining screw 28, as shown in Figure 2. Such a key serves to effectually lock the pulley and spindle against relative rotation while permitting freer sliding movement than would result from the use of the usual bar key. While the extension 27 and its use to support the pulley as shown is preferred, this extension is not essential. It may be omitted, in which case the pulley 25 might well be rigidly secured to the spindle in any suitable manner as the axial movement of the spindle would ordinarily be taken up by the drive belt.

As best shown in Figure 1, the upper and lower bearing blocks 20 and 21, which support the opposite ends of the piston stem, extend radially from said stem and are rigidly secured to one another by a combined brace and stop rod 5. The connection between the rod 5 and these bearing blocks is a rigid and immovable connection, so as to firmly tie together the piston stem and the rod 5 as clearly shown in Figure 4. The rod 5 extends vertically through the bearing 4 of a length even greater than the effective length of the cylinder 2. The rod 4 is made of sufficient cross section to resist twisting or bending strains and, inasmuch as it extends through the long bearing 4, it serves to positively support the bearings at the opposite ends of the piston stem in such manner as to eliminate all bending stresses on said stem. Moreover, this rod and the bearing blocks 20 and 21 move with the stem and thus support and guide it at all times. This fact, together with the further fact that the stem extends through the sleeves 9 between the bearing blocks, assures absolute alignment of the sleeve at all times and eliminates binding of the spindle within the sleeve. These facts are important, particularly in conjunction with the further fact that the piston stem and spindle axially move with one another and are tied together against relative axial movement. There is thus practically no wear between any part of the sleeve and spindle and the spindle is thus caused to run true and without whip or radial lost motion. Consequently the drill bit will drill accurately for unlimited periods. The rod 5 is threaded and provided above and below the body with adjusting nuts 29 and lock nuts 30 to control the throw of the piston in both directions.

As hereinbefore stated, the piston is shown as double acting and it is adapted to be pneumatically operated in both directions by compressed air admitted through tapped holes 31, formed in the end caps 6 and 7 of the cylinder. A number of these tapped holes are provided in each cap and any

one of such holes in each cap may be utilized, as may be most convenient to the air supply. Those utilized are fitted with hose connecting nipples 32, as shown in Figure 2, while the others are sealed by threaded plugs 33. Ducts 34 lead from each of the tapped holes 31 to the interior of the corresponding end of the cylinder. Air under pressure is thus admitted into the opposite ends of the cylinder, with the admission and release controlled by appropriate air valves associated with the compressed air supply system and forming no part of the present invention.

While the piston has been shown as double acting, it may be made single acting in a downward direction and a spring 35 may be utilized to elevate the piston during the retractive movement of the drill bit. In fact the spring may be used even with a double acting piston to speed up the retraction of the drill bit. If a single acting piston is employed, one or more of the tapped holes 31 in the lower cap should be left open.

It will be apparent from the foregoing detailed description, that the structure of this unit is extremely simple. The parts require very little machining and standard bearings may be used. The body of the tool may be extruded, as stated, and standard parts may be used for many parts of the structure. Consequently this unit can be very cheaply manufactured and sold at a much lower price than is ordinarily the case for units of this general character.

Furthermore, the parts are so compact that the overall cross sectional dimensions may be made extremely small and yet the unit will function with high efficiency. With such small cross sectional dimensions, a number of these tools may be mounted, by means of any desired brackets, stands or other means, with the drill bits very close to one another, so that a number of holes may be drilled simultaneously in very close proximity to one another. This is in marked contradistinction to the usual prior practice where it is frequently necessary to shift the work between drilling operations on holes in close proximity.

The foregoing detailed description sets forth the invention in its preferred practical form, but the invention is to be understood as fully commensurate with the appended claims.

Having thus fully described the invention, what I claim as new and desire to secure by Letters Patent is:

1. A drill unit comprising: an elongated body provided longitudinally thereof with a cylinder chamber and a combined brace and stop rod bearing laterally of said chamber and extending parallel thereto, cylinder caps at the opposite ends of said cylinder, a piston in said cylinder having a tubular piston stem coaxial of and extending from both sides of the piston through both cylinder caps, bearing blocks mounted on the opposite ends of said stem and extending laterally therefrom, a combined brace and stop rod slidably mounted in and extending through the bearing in the body with its opposite ends rigidly and immovably secured to said bearing blocks to rigidly secure the piston stem to the brace and stop rod, stop nuts threaded on to the stop rod beyond the opposite ends of said body to limit the throw of the piston on both directions, a spindle extending through and coaxially with the tubular piston stem and mounted in bearings carried by the bearing blocks, means for securing the spindle against axial movement relative to the piston stem, the rigid connection between the brace and stop

rod, the blocks, and the stem functioning to retain the stem in true alignment whereby to eliminate binding of the spindle within the stem, means for rotating the spindle, and means for introducing compressed air into the cylinder to operate the piston to axially reciprocate the stem and brace and stop rod as a unit.

2. A drill unit comprising: an elongated body with a cylinder chamber and a guide bearing extending in parallel spaced apart relation from one end to the other end of said body, a piston in the cylinder chamber, said piston having a tubular stem slidably mounted within and extending beyond both ends of said cylinder chamber, a spindle rotatably passing through the tubular stem and locked against axial movement relative thereto, blocks mounted on the opposite ends of said stem and extending laterally therefrom, a brace rod slidably mounted in and extending through the guide bearing with its opposite ends rigidly and immovably connected to said blocks to rigidly secure the piston stem to the brace rod, whereby to retain the stem in true alignment and eliminate binding of the spindle within the stem, means to rotate the spindle, and means to axially reciprocate the piston, stem and brace rod as a unit.

3. A drill unit comprising: an elongated body with a chamber and a guide bearing extending in parallel spaced apart relation from one end

5
